UNITED STATES PATENT OFFICE.

BENJAMIN F. FOWLER, OF MINNEAPOLIS, MINNESOTA.

FOLDING BED.

1,303,875.

Specification of Letters Patent.

Patented May 20, 1919.

Application filed August 7, 1915. Serial No. 44,230.

To all whom it may concern:

Be it known that I, BENJAMIN F. FOWLER, a citizen of the United States, resident of Minneapolis, county of Hennepin, State of Minnesota, have invented certain new and useful Improvements in Folding Beds, of which the following is a specification.

The object of my invention is to provide a bed adapted to be swung down into the room 10 for use and raised to an upright position within a closet door opening for concealing the entrance to the closet and allowing access to the closet in the rear of the bed.

A further object is to provide a folding 15 bed in which all counter-weights are eliminated and in which there will be absolutely no danger of the bed accidentally closing.

Other objects of the invention will appear 20 from the following detailed description.

The invention consists generally in various 25 constructions and combinations, all as hereinafter described and particularly pointed out in the claims.

In the accompanying drawings forming 30 part of this specification,

Figure 1 is a view of a closet door frame, showing the bed raised and closing the opening,

Fig. 2 is a vertical sectional view, trans- 35 versely of the bed and the opening,

Fig. 3 is a horizontal sectional view of the same,

Fig. 4 is a vertical sectional view, showing 40 the bed lowered to a horizontal position,

Fig. 5 is a vertical sectional view, showing the device for counter-balancing the weight 45 of the bed and preventing its accidental closing.

In the drawing, 2 represents a door frame, 40 through which access is had to the closet 3. 4 is a frame or casing, mounted to slide in a guide-way 5 in the floor of the closet and having a hanger 6 provided with an anti-friction roll 7 to ride on a supporting rod 45 8 in the top of the closet near the outer walls thereof. 9 is a panel, forming the door of the closet and also the bottom of the bed and having legs 10 and an ordinary bed spring 11 mounted thereon. Brackets 12 50 are mounted on the inner end of said panel and have slots 13 therein to receive anti-friction wheels 14 mounted in the side walls of the casing 4. Sheaves 15 are mounted in the walls of the casing and cables 16 are attached at one end to counter-balance springs 55

17 and pass under the sheaves 15 and are connected at 18 to the brackets 12.

Anti-friction rollers 19 are mounted in the brackets 12 to bear on a plate 20 that is hinged at 21 to the wall of the casing and 60 a spring 22 is mounted to bear on the plate 20 and resist outward movement thereof when the bed is pulled down to a horizontal position, and rollers 19 bearing on the plate 20 will push it outwardly against the tension 65 of the spring and resist the downward movement of the bed and at the same time the springs 17 will be put under tension by the downward pull of the cables 16 thereon. When the bed approaches its horizontal po- 70 sition, the rollers 19 will have passed the center of the axis of the bed and the pressure of the rollers on the plate will be relieved and the spring will return the plate to its normal position as indicated in Fig. 4, while 75 the springs 17 will be under tension to assist in the initial raising of the bed.

As indicated in Fig. 3, the bed is mounted to slide back in the closet in a plane parallel with the door opening, so that sufficient 80 space will be provided to allow a person to enter the closet and pass in back of the bed. When, however, the bed is pulled forward, the closet door opening will be entirely closed and the bottom of the bed will present 85 the appearance of an ordinary closet door and the bed may be lowered through the opening to its open position.

The bed when pushed back into the closet will not be visible and when pulled forward 90 in front of the door opening will form a comparatively close joint with the door casing and present a neat, finished appearance and at the same time exclude dust and dirt from the closet where clothing may be hang- 95 ing. In reality, the bed when pulled to a point opposite the door opening, has the appearance of a closed door. When the bed is positioned opposite the opening, it may be easily and quickly lowered to a horizontal 100 position, ready for use. The details in the manner of mounting the bed on the wall of the closet may be varied to suit different conditions of installation and still be within the scope of my invention.

I claim as my invention:

1. The combination, with a wall having a closet in the rear thereof and provided with an opening for access to said closet, of a track mounted in said closet above said 110

opening and extending across the same, a casing suspended on said track to move from a concealed position within the closet to a position opposite said opening, said casing being seated against the frame of said opening on the inside of the closet when positioned opposite said opening and forming a comparatively close joint with said frame, and a bed mounted in said casing to swing outwardly and downwardly through said opening to a horizontal position, said bed being wholly concealed when said casing is withdrawn from the position opposite said opening and the underside of said bed being fashioned to represent a door for said closet when said casing is moved to a position to close said opening.

2. The combination, with a wall having a closet in the rear thereof and provided with an opening for access to said closet, of a track mounted in said closet above said opening and extending across the same, a casing suspended on said track to move from a concealed position within the closet to a position opposite said opening, said casing being seated against the frame of said opening on the inside of the closet when positioned opposite said opening and forming a comparatively close joint with said frame, and a bed mounted in said casing to swing outwardly and downwardly through said opening to a horizontal position.

tion, said bed being wholly concealed when said casing is withdrawn from the position opposite said opening and the underside of 35 said bed being fashioned to represent a door for said closet when said casing is moved to a position to close said opening, and guides provided in said closet for the lower end of said casing for holding it in its 40 vertical position during its movement in said closet.

3. The combination, with a wall having a closet in the rear thereof and provided with an opening for access to said closet, of a 45 track mounted in said closet and extending across said opening, a casing supported on said track for movement back and forth thereon from a concealed position within said closet to a position opposite said opening, said casing lapping by the frame of 50 said opening and forming a comparatively close joint therewith to close said opening when positioned opposite the same, and a bed mounted in said casing and normally 55 concealed when said casing is withdrawn from its position opposite said opening and adapted to swing outwardly and downwardly through said opening when said casing is positioned to close the same. 60

In witness whereof, I have hereunto set my hand this 29th day of July, 1915.

BENJAMIN F. FOWLER.
